[57] CLAIM

The ornamental design for a display rack for packaged produce, substantially as shown and described.

DESCRIPTION

FIG. 1 is a perspective view of a display rack for packaged produce showing my new design;

FIG. 2 is a side elevational view thereof;

FIG. 3 is a top plan view thereof;

FIG. 4 is a bottom plan view thereof;

FIG. 5 is an enlarged front elevational view thereof;

FIG. 6 is an enlarged rear elevational view thereof;

FIG. 7 is an enlarged cross sectional view taken along line 7—7 of FIG. 1;

FIG. 8 is a side elevational view of a modified embodiment of a display rack for packaged produce;

FIG. 9 is a top plan view thereof;

FIG. 10 is a bottom plan view thereof;

FIG. 11 is a front elevational view thereof; and

FIG. 12 is a rear elevational view thereof.
